UNITED STATES PATENT OFFICE

165,768

LADY'S STOCKING

Otto E. Kuehnert, Selinsgrove, Pa., assignor of fifty per cent to Nellie Kuehnert, Selinsgrove, Pa.

Application May 3, 1949, Serial No. 2,410

Term of patent 3½ years

(Cl. D47—7)

To all whom it may concern:

Be it known that I, Otto E. Kuehnert, a citizen of the United States, residing at Selinsgrove, in the county of Snyder, and State of Pennsylvania, have invented a new, original, and ornamental Design for Lady's Stocking, of which the following is a specification, reference being had to the accompanying drawing, forming part thereof.

The dominant features of my design reside in the line configuration in lieu of the usual heel reinforcement, said line configuration terminating in divergent lines at the back of the ankle region.

I claim:

The ornamental design for a lady's stocking, as shown and described.

OTTO E. KUEHNERT.
